[57] CLAIM

The design for a air stone, as shown and described.

DESCRIPTION

FIG. 1 is a front perspective view of air stone showing my new design;

FIG. 2 is a front elevational view thereof;

FIG. 3 is a rear elevational thereof;

FIG. 4 is a side elevational view thereof, the opposite side being a mirror image of the side shown;

FIG. 5 is a top plan view thereof; and,

FIG. 6 is a bottom plan view thereof.

*Fig. 1**Fig. 2**Fig. 3**Fig. 6**Fig. 5**Fig. 4*
